2 Claims. (Cl. 204—224)

The invention relates to a D.C. source serving to feed apparatus for electrolytic metal machining, more particularly electrolytic grinding. In such apparatus, an electrically conducting liquid is placed between a tool electrode, which generally constitutes a metal-bonded diamond grinding wheel, and a workpiece electrode, and the work-piece and the prinding wheel are connected to the two poles of a D.C. source. As a result of the electrolytic action of the electric current, the material at the work-piece, which is connected with anode polarity, is removed. In the case of electrolytic grinding with metal-bonded diamond wheels, the basic mechanical removal process is greatly increased.

The special advantages of this grinding process have full effect, however, only if a short-circuit current limiting system in the D.C. source prevents thermal damage of the workpiece and grinding wheel as a result of excessive currents in the case of direct metallically conductive contact. Moreover, additional spark or arc erosion parallel with the electrolytic process must be prevented. The sparks or arcs not only result in a coarsening of the surface of the workpiece but also greatly increased wear of the tool, particularly the expensive diamond grinding wheels. The sparks or arcs occur if the voltage between the workpiece and the tool reaches or exceeds the arc limit voltage. This arc limit voltage is dependent upon the material of the workpiece and of the tool and also on the electrolyte used. It is generally about 14 volts. As a result of the inevitable internal inductance of the D.C. sources conventionally used for electrolytic grinding voltage peaks exceeding the arc limit voltage at the machining gap between the workpiece and the tool during operation cannot be avoided. The output voltage U_A is obtained from the following:

$$U_A = U_L - R_1 \cdot I - L_1 \frac{dI}{dt}$$

where U_L is the no-load voltage

R_1 is the internal resistance and

L_1 is the internal inductance of the D.C. source.

Since the resistance between the workpiece and the wheel generally continually varies during grinding, for example as a result of differences in the distance of the surface being ground from the wheel, or as a result of differences in the condition of the electrolyte, rapid and considerable fluctuations in the output current of the D.C. source are inevitable. As a result, voltage peaks far above the arc limit voltage may occur if the working current is reduced or interrupted for a short time, particularly since the no-load voltage has to be made relatively high in view of the required removal capacity.

Control devices have already been disclosed which prevent excessive voltage increase during no-load operation. Control devices are also known by means of which the voltage between the tool electrode and the workpiece can be reduced if a high-frequency current component occurs in the circuit as a result of arc or spark discharges. The occurrence of sparks or arcs can thus be detected by this control device and the voltage of the D.C. source

can be reduced. This generally obviates any considerable damage but it is a disadvantage that the mean value of the working voltage has to be kept relatively low during the entire machining process, and this is at the expense of the removal capacity.

All devices known hitherto counteract the effects but not the causes of the disturbances.

For this reason, according to an undisclosed proposal it has been suggested that the signal used to control the output voltage of a D.C. source should be a magnitude corresponding to the first differential quotient of the output current by time, so that the cause of disturbances, namely the internal inductance of the current source, was rendered inoperative. The latter arrangement is admittedly very advantageous as regards its action, particularly in the case of relatively high powers, but is also relatively expensive.

According to the invention, in contradistinction thereto, a D.C. source is proposed for electrolytic metal machining, more particularly electrolytic grinding, by means of which the arc of spark formation can be effectively suppressed without the mean value of the working voltage having to be kept very much below the arc limit voltage, and which can be embodied with very simple circuitry. The D.C. source according to the invention is characterized in that the D.C. output is bridged by a Zener diode, the breakdown voltage of which is lower than the arc limit voltage of the workpiece electrode and tool electrode material combination. By a Zener diode is meant a semi-conductor diode which becomes conductive again in the inverse direction if the inverse voltage applied exceeds the so-called breakdown or Zener voltage and which then has a very low internal resistance. The magnitude of the Zener voltage depends on the manufacturing process of the diode and can thus be predetermined.

Thus no voltages appreciably higher than the breakdown voltage can occur at the Zener diode since this diode acts practically as a short-circuit to such voltages. If the Zener diode breakdown voltage is chosen to be slightly below the arc limit voltage and a diode dimensioned in this way is connected in parallel with the output of the D.C. source and hence also in parallel with the workpiece and the grinding wheel, no voltages higher than the arc limit voltage can occur between the workpiece and the grinding wheel.

If the D.C. source no-load voltage is made smaller than or equal to the Zener diode breakdown voltage, the Zener diode need only destroy that proportion of the electrical energy stored in the magnetic field of the internal inductance of the current source which is liberated during the periods of decreasing anode current. This energy, however, is only a small proportion of the total energy used during the grinding process.

However in special cases, in the case of high powers, it may occur that the electrical energy to be absorbed by the Zener diode exceeds its admissible power loss. According to the invention, it is therefore proposed to reduce the power converted in the Zener diode by bridging the Zener diode by means of a series-connected resistance-condenser combination which can absorb part of the magnetic energy liberated during grinding from the D.C. source, and to connect the two ends of the resistance additionally to a regulator which in turn acts on a voltage control element arranged in the primary circuit of the D.C. source. The control magnitude tapped from the resistance contains the first differential quotient of the output current according to time in these conditions.

The control magnitude corresponding to the first differential quotient of the output current according to time may naturally be obtained in some other way, for example by means of a transformer, the primary side of which is connected in the output circuit.

Using a Zener diode it is thus possible, in the case of very high powers, advantageously to combine other already proposed steps for avoiding sparking or arcing. This results in a considerable reduction of the cost of the entire plant because security against sparking or arcing is ensured by the Zener diode connected according to the invention and the control circuit components added to relieve the Zener diode can be given much lower value than if they alone had to prevent arcing, while the grinding capacity remains the same.

The D.C. source according to the invention and its effect will be explained in detail hereinbelow with reference to the drawings.

FIG. 1 is a schematic circuit diagram of a D.C. source incorporating a Zener diode, while

FIG. 2 is an example of the output voltage per unit of time with and without a Zener diode.

FIG. 3 is a schematic circuit diagram of one embodiment of the invention.

FIG. 4 is a schematic circuit diagram of a second embodiment of the invention.

In FIG. 1, the output terminals 1 and 2 of the D.C. source with the internal resistance R_1 and the internal inductance L_1 are connected to the workpiece 4 and the grinding wheel 5, and the two poles of the D.C. source are bridged by a Zener diode 6, the breakdown voltage of which is below the arc limit voltage.

In FIG. 2, the solid-line curve corresponds to the voltage without a Zener diode, while the broken-line curve corresponds to the voltage curve with the Zener diode. The arc limit voltage is shown in chain-dotted lines.

In the circuit according to the invention shown in FIG. 3, the Zener diode is bridged by a series-connected resistance-condenser combination 7, 8. A control magnitude which corresponds to the first differential quotient of the output current according to time and which is supplied to the regulator 9 is tapped from the resistance 7. The regulator 9 which in the simplest case may be a grid-controlled electronic tube acts on the control element 10 of the D.C. source 3. This additional control reduces the power converted in the Zener diode.

A second embodiment of the invention is shown in FIG. 4. Certain elements of the arrangement of FIG. 4 correspond to those of FIG. 3. These elements are identified by like numerals. The principal distinction between the two embodiments illustrated is that in the arrangement shown in FIG. 4, the control magnitude corresponding to the first differential quotient of the output current according to time is coupled to the regulator 9 by a transformer 11. This is accomplished by connecting the transformer primary winding in the output circuit between the workpiece 4 and resistor 7. The secondary winding of transformer 11 is connected to the regulator 9.

What I claim is:

1. In an electro-erosion machining apparatus an electric operating circuit comprising a direct current source, a tool electrode connected to said source, a workpiece electrode connected to said source, and a working gap in said circuit between said tool electrode and said workpiece electrode, said gap being filled with an electrolyte, a non-linear resistor connected across said working gap, said non-linear resistor comprising a Zener diode having a breakdown voltage which is lower than the critical arcing or sparking voltage across the working gap between said tool and workpiece electrodes, a bridging arrangement across said Zener diode, said bridging arrangement comprising a series combination of a resistor and a condenser in parallel with said Zener diode, and a regulator coupled to said circuit, said regulator responding to the rate of change of the working current in said circuit to regulate the voltage of said direct current source.

2. In an electro-erosion machining apparatus an electric operating circuit comprising a direct current source, a tool electrode connected to said source, a workpiece electrode connected to said source, and a working gap in said circuit between said tool electrodes and said workpiece electrode, said gap being filled with an electrolyte, a non-linear resistor connected across said working gap, said non-linear resistor comprising a Zener diode having a breakdown voltage which is lower than the critical arcing or sparking voltage across the working gap between said tool and workpiece electrodes, a bridging arrangement across said Zener diode, said bridging arrangement comprising a series combination of a resistor and a condenser in parallel with said Zener diode, and a transformer having its primary winding connected in said circuit, a regulator connected to the secondary winding of said circuit and thereby coupled to said circuit, said regulator responding to the rate of change of the working current in said transformer to regulate the voltage of said direct current source.
